UNITED STATES PATENT OFFICE.

GEORGE WILCOX, OF RIVERSIDE, CALIFORNIA, ASSIGNOR TO CALIFORNIA CANNING MACHINERY CO., A CORPORATION OF CALIFORNIA.

PREHEATER.

Application filed November 10, 1923. Serial No. 674,095.

This invention relates to cannery equipment and relates particularly to a device in which cans of foodstuffs, previous to sealing and cooking, may be raised to a temperature sufficient to expand and thereby exhaust a portion of the air from the cans.

Devices of this character are commonly termed exhaust boxes, from the fact that they are employed for the purpose of exhausting air from the cans before they are sealed. It is customary to employ a suitably heated housing in which a conveyor operates, the cans being placed on the conveyor at one end of the exhaust box, carried through the heated interior of the exhaust box, and discharged from the other end of the conveyor.

It is an object of the invention to provide a preheating device of this character having a materially increased efficiency as compared with the present types of exhaust boxes, this efficiency being chiefly due to the use of mechanism which enables the carrying of the cans through upper and lower horizontal laps a course substantially twice the length of the course through which the cans are carried in present types of exhaust boxes occupying the same floor space. This very material increase in efficiency is of considerable importance as it enables the conservation of floor space in packing plants.

The invention has for a further object to provide means for reducing the loss of heat from the interior of the exhaust box through the escape of steam through the openings therein.

My invention employs an arrangement of doors in the entrance and discharge openings to the heated chamber which are so arranged that each passage is always closed by one or more doors. This arrangement permits but very little escape of heat from the interior and thus contributes to the efficiency thereof and improves the working conditions surrounding the machine by preventing excessive escape of heat into the atmosphere.

In the following description of my invention, the advantages and further objects of the invention will be made fully evident.

Referring to the drawings which are for illustrative purposes only,

Fig. 1 is a plan view taken in section substantially on a line indicated as 1—1 of Fig. 2.

Fig. 2 is a section taken on the line 2—2 of Fig. 1.

Fig. 3 is a vertical cross section taken as indicated by line 3—3 of Fig. 2.

Fig. 4 is a fragmentary view taken as indicated by the line 4—4 of Fig. 2, for the purpose of showing the placement of guide bars for directing the cans through a flattened helical course.

Fig. 5 is a diagrammatic elevation showing the arrangement of drive gears.

Fig. 6 is a fragmentary sectional view taken on a plane indicated by the line 6—6 of Fig. 1.

Fig. 7 is a fragmentary plan view showing the manner in which I apply doors to the discharge opening of the device.

Fig. 8 is a fragmentary plan view showing the manner in which the doors are applied to the entrance opening.

Fig. 9 is a section taken substantially on a plane indicated by the line 9—9 of Fig. 8.

Fig. 10 is an enlarged fragmentary view of the can feeding mechanism.

In the form of my invention shown in the drawings, carrying members are provided in the form of trays 11. These carrying members are moved continuously through a flattened somewhat elliptical path or orbit by flexible traveling members which may be in the form of sprocket chains or of link belts 12 which travel over sprocket wheels 13 and 14 secured upon shafts 15 and 16. The trays adapted to support articles upright during their repeated passage above and below both of said sprocket wheels and through substantially horizontal laps therebetween, are shown as pivotally supported upon the chain belts in bearings 19 through which shaft members 20 extend. The trays 11 may be rigidly secured to the shaft member and are maintained in substantially flat or horizontal position, during their advance through the mentioned non-circular orbits by means such as arms 22 which are shown as mounted upon the rightward ends of the shaft members 20.

Mounted in positions slightly forward and to the right hand side of the sprockets 13

and 14 is a pair of sprocket wheels 23 and 24 which are of substantially the same diameter as the sprocket wheels 13 and 14. Over the wheels 23 and 24 a linked chain belt 25 is extended, this chain belt having inwardly projecting lugs 26 which engage the ends of the lever arms 22, the majority of which are forked, but of which one or two are provided with eyes 28, as indicated in Fig. 2, 10 which tie the chains 12 and 25 together so that the chain 25 will be driven synchronously with the chain 12. The sprocket wheels 23 and 24 rotate at the same rate of speed as the wheels 13 and 14, therefore, the lugs 15 26 on the belt 25 are moved, in spaced relationship with corresponding shaft members 20, through a flattened orbit indicated by the dotted lines 27 of Fig. 2, this orbit 27 being of the same size as the orbit through 20 which the shafts 20 travel but being disposed a distance forward from the orbit of the shaft members 20, this distance being equal to the length of the arms 22. By this arrangement the extension of the arms 22 is 25 maintained in horizontal direction, no matter what position in the orbit of travel they may assume. The trays 11 being rigidly secured upon the shaft members 20, are likewise maintained in positions substantially 30 parallel to a horizontal plane. Any cans, or other objects to be treated, which are placed upon the trays will pass through a helical orbit but will be maintained in erect position so that spilling of liquid or other contents 35 therefrom is effectually prevented.

The cans, as indicated at 30 in Fig. 1, are placed upon the trays in a single row, at the rightward side of the machine, each can being carried forwardly upon the rightward 40 end of a tray to the rear of the machine whereupon it is lowered with the travel of the belt 12 downwardly over the forward sprocket wheels 14 and is then brought rearwardly along the underside of the belt as indicated 45 by the arrow 32 in Fig. 2 and upon reaching the forward end of the machine is carried upwardly due to the travel of the belts 12 over the forward sprocket wheels 13. During the initial forward travel of a can as 50 indicated by the arrow 34 in Fig. 1, it is engaged by a diagonally disposed guide bar 35 which moves it in a leftward direction as the tray upon which it is carried advances. When the can has reached the end of its forward movement and starts downwardly with the tray as indicated in dotted lines 37, it 55 will have been moved by the guide bar 35 into a position a short distance from the rightward end of the tray and in position as indicated by dotted lines 38 in Fig. 4 to enter the passage 39 between the lower guide bars 40 and 41. During the rearward travel of the can, it is moved to the left by the guide bar 40 and at the end of the rearward travel 60 65 is in the position indicated at 42 in Fig. 4

from which it is carried upwardly into the upper channel 44 formed between the guide bars 45 and 46.

It will be recognized that by moving the cans laterally during their travel through a definite orbit, a helical path of somewhat flattened character is described. By suitably varying the width of the machine, this helical path may be made of suitable length, thus causing the cans to be carried back and forth within the preheater device quite a number of times before being discharged at the leftward side of the chamber in which the carrying members or trays 11 are situated. This structure, which provides a helical travel of the cans through the preheater, is of very simple and economical construction as compared to the standard arrangement of conveyors employed to accomplish the same amount of travel within an exhaust box.

The mechanical elements hereinbefore described are mounted in any suitable structure, such as structural channel members 50 suitably erected in the form of frame work 51 as indicated in Figs. 1, 2, and 3. Although in the use of the device, it is intended to inclose the structure with substantially tight walls of sheet metal and insulating material, these walls have been omitted in Figs. 1, 2, and 3 in order that the features of construction and arrangement may not be obscured.

My invention provides an improved form of mechanism whereby the cans may be fed into the preheater. As shown in Fig. 1, a circular table 55 is mounted upon a vertical shaft 56, this table rotating in the direction indicated by the arrow 57 so that any cans placed thereon as indicated at 58 will be carried through a part-circular course and guided up onto a trackway or slide 60 along which they are moved in the forward direction, indicated by the arrow 34, by projecting arms 61 mounted upon a chain belt 62 which travels over sprockets 63 and 64. Stationary guides 162 and 163 are provided for directing the cans into the path of the projecting arm 61, and resiliently disposed guide members 65 and 66 are provided for the purpose of distributing the cans properly in the pockets formed between the consecutive projections 61. The form and operation of these resiliently disposed guide members constitute an important feature of the invention as they prevent the jamming of cans against the ends of the pusher arms 61 which often occurs in canning machines and is productive of much trouble and delay.

It will be readily recognized that a can might be placed upon the rotating table 55 in such a manner that it would meet with the end of one of the pusher members 61 and would not properly engage a pocket between the pusher members. The resiliently disposed guide members 65 and 66 are placed

parallel to the path of the member 61 so that in case a can comes against the end of one of these pusher members it will be engaged by the forward ends 67 of the members 65 and 66, whereupon occurs a rolling action along the member 66 which it will be noted is substantially straight in extension and is formed of a pair of bars 69 providing an opening therebetween in which the member 65 swings. Due to the engagement of the members 66 with the can, its movement is retarded so that it will drop into a position behind the pusher member 61 with which it originally made end engagement. The member 65 is rearwardly bent at 70 near the forward end thereof so that a pocket is formed. The presence of this pocket permits the member 65 to swing inwardly around a can 71, Fig. 10, so that the forward end thereof will be in a position to engage and retard the movement of a following can such as indicated at 72, thus preventing the bunching up of the cans against the pusher member. The members 65 and 66 are forced resiliently in the direction indicated by the arrow 73 by springs 74 and 75 which connect between a stationary bar 76 and arms 77 and 78, the arm 77 being mounted upon the vertical shaft 79 to which the bars 69 constituting the member 66 are secured, and the arm 78 extending rearwardly from the member 65 which is pivotally mounted upon the shaft 79.

The cans are discharged from the preheater along a trackway 80 which is similar in construction to the trackway 60.

It will be noticed that the bottom members 81 of the trackway end in fingers 82 which terminate on vertical planes which substantially coincide with the axes of the forward and rearward pairs of sprocket wheels 13 and 14. The members 81 are disposed on the level of the upper plane of travel of the trays 11 and the fingers extend into notches 85 provided near the ends of the trays, thus making it possible for the cans to move from trackway to tray and from tray to trackway in a very smooth and even manner. As shown in Fig. 1, the belt member 87, traveling over sprocket wheels 88 and 89, is provided with projecting pusher arms 90 which have the function of engaging the cans when they are in position to leave the trays, as indicated at 91, and to move the cans along the trackway 80 from which they are taken to the next operation.

The belts 62 and 87, Fig. 1, are driven synchronously with the chain belts 12 so that the pusher arms are timed with the movement of the trays 11. The driving of the whole machine may be accomplished through the engagement of a motor driven belt, not shown, with the pulley 100, this pulley 100 driving a shaft 101 having a bevel gear 102 mounted intermediately thereupon and a spur gear 103 at the end thereof. The bevel gear

102 engages a bevel gear 104 which, as shown in Fig. 2, causes the rotation of the shaft 56 through a shaft 107 and gears 108 and 109, thus causing the rotation of the circular table 55. Through an idler gear 110, a large gear 111, Figs. 3 and 5, is driven. This gear 111 is keyed upon the shaft 15 which carries the forward pair of sprocket wheels 13, thus causing the driving of the link belts 12. The chain belt 62 which constitutes part of the feeding mechanism is driven from a sprocket wheel 115 mounted upon the shaft 15 through a chain 116, a shaft 117, gears 118 and 119 which drive the vertical shaft 120 which supports the sprocket 64 carrying the rearward end of the chain 62.

The forward sprocket wheels 14 are mounted upon the shaft 16. Upon the outer leftward end of the shaft 16 a sprocket 122 is secured, as shown in Fig. 1, and indicated in the dotted lines 122 in Fig. 2. The sprocket 88, over which the chain belt 87 travels, is mounted upon a vertical shaft 125 as shown in Fig. 6. This shaft has a bevel gear 127 mounted thereon, which is driven by a bevel gear 128 mounted on a shaft 129, which also has mounted thereon a sprocket 130 which is driven from the sprocket 122 by a chain belt 132, Figs. 1, 2 and 6.

In the use of the invention, it is desirable to enclose the frame structure with metal plates 135, as shown in Figs. 7 and 8, thus forming a chamber in which the traveling mechanism is placed. The chamber thus formed may be interiorly heated by steam coils or other heating means, not shown. In the standard forms of preheaters, considerable loss of heat results from the escape of heated vapors and gases through the entrance and exit openings of the exhaust chamber. In Figs. 7 and 8, I show the manner in which doors 138 and 139 are employed in the practice of my invention. The trackways 60 and 80 are housed in with side, top and bottom wall members 140, as shown fully in Fig. 9, in this manner forming a tubular channel through which the cans must pass as they enter or leave the preheating device. The doors may be hinged as indicated at 142 and are spaced at such distance apart relative to the spacing of the cans that only one door may be held open by the passing of a can at a certain time. As shown in Fig. 8, a can 145 is shown forcing the door 138 open.

It will be recognized that when the can 145 moves into the position indicated by the dotted lines 146, the door 138 will be permitted to swing closed and will therefore be in closed position when the can 145 engages and opens the door 139. These doors may be fitted with a fair degree of accuracy so as to provide an efficient closure of the inlet and outlet passages. Any suitable spring means, such as indicated at 150, may be em-

ployed for the purpose of holding the doors 138 and 139 resiliently in closed position.

I claim as my invention:

1. In a preheating organization, the combination of a treating chamber; a plurality of carrying members arranged to receive objects to be treated and to hold said objects in an upright position; flexible traveling members extending over wheels upon which 10 said carrying members are advanced through a flattened elliptical orbit; means for moving said objects in a direction transverse to the direction of advance of said carrying members, in a manner causing the passage of 15 said objects through said treating chamber in a substantially helical path, and sets of spaced and resiliently closed doors positioned in the openings of said heating chamber, and operating in a substantially vertical 20 plane under contact with said advancing objects, in such a manner to maintain constantly closed openings to said heating chamber.

2. In a preheating organization, the combination of a treating chamber; a plurality of carrying members arranged to receive objects to be treated and to hold said objects in an upright position; flexible traveling members, extending over wheels upon which 30 said carrying members are advanced through a flattened elliptical orbit; means for moving said objects in a direction transverse to the direction of advance of said carrying members, in a manner causing the passage of said 35 objects through said treating chamber in a substantially helical path; sets of spaced and resiliently closed doors positioned in the openings of said heating chamber, and operating in a substantially vertical plan under contact with said advancing objects, in such a manner to maintain constantly closed 40 openings to said heating chamber; a feeding member for placing said objects upon said carrying members; resiliently disposed means for guiding said objects into engagement with said feeding means; and walls enclosing the mentioned parts.

3. In a preheating organization, the combination of a treating chamber; a plurality of carrying members arranged to receive objects to be treated and to hold said objects in an upright position; flexible traveling members extending over wheels upon which 50 said carrying members are advanced through a flattened elliptical orbit; means for moving said objects in a direction transverse to the direction of advance of said carrying members, in a manner causing the passage of said objects through said treating chamber 55 in a substantially helical path; a feeding member for placing said objects upon said carrying member during the continuous advance of the latter; a rotating table upon which said objects are placed and carried into engagement with said feeding member;

resiliently disposed means for guiding said objects into engagement with said feeding means; and walls enclosing the mentioned parts.

4. In a preheating organization, the combination of a treating chamber provided with diagonally opposed openings constantly closed by spaced and resiliently closing doors; a plurality of carrying members arranged to receive the objects to be treated and 70 to hold said objects in an upright position; means, including flexible traveling members, whereby said carrying members are moved through a non-circular orbit; a feeding member for placing said objects upon said carrying members; a rotating table upon which said objects are placed and carried into engagement with said feeding member; resiliently disposed means for guiding said objects into engagement with said feeding means; and means for moving said objects sideways upon said carrying members during the continuous advance of said carrying members; said treating objects being carried through a substantially helical path between 75 said openings as said carrying members are moved through said orbit.

5. In a preheating organization, the combination of a treating chamber provided with entrance and exit openings constantly closed by spaced and resiliently closing doors; a plurality of carrying members arranged to receive objects to be treated and to hold said objects in substantially upright positions; a flexible traveling member extending over 80 wheels moving said carrying members continuously through a non-circular orbit; means for maintaining said carrying members substantially parallel to a horizontal plane; cam means for sliding said objects 85 sideways on said carrying members, causing said objects to be carried between said sets of doors through a substantially helical path as said carrying members are moved through 90 said orbit, and means for moving said objects 95 through said doors in a manner maintaining constantly closed openings in said chamber.

6. In a preheating organization, the combination of a treating chamber, provided with openings, constantly closed by spaced and resiliently closing doors; a plurality of carrying members, arranged to receive objects to be treated and to hold said objects in a substantially upright position; a flexible traveling member, extending over wheels, moving said carrying members through a non-circular orbit; means for maintaining said carrying members substantially parallel to a horizontal plane; a feeding member for placing said objects upon said carrying members; a rotating table upon which said objects are placed and carried into engagement with said feeding member; resiliently disposed means for guiding said objects into engagement with said feeding means; and means 100 105 110 115 120 125 130 135

for sliding said objects sidewise upon said carrying members in a manner causing the passage of said objects through said orbit in a flattened elliptical path having upper and 5 lower horizontal laps.

7. In a mechanism for feeding objects into a machine, the combination of: a treating chamber provided with openings; spaced doors, pivotally mounted in said openings 10 and movable by said objects in a vertical plane; a flexible traveling member; engagement members movable by said traveling member in a non-circular orbit; and resiliently maintained guide members disposed 15 along the path of said engagement members and arranged to bear separately against said objects at consecutive points along the path through which said objects are carried by said engagement members.

20 8. In a mechanism for feeding objects into a machine, the combination of: flexible traveling members provided with means for advancing the same in non-circular orbits; engagement members moved by said traveling member; a rotating table upon which said objects are placed and thereby carried into the path of said engagement members; resiliently maintained guide members disposed along the path of said engagement members, 25 said guide members being arranged so as to bear separately against said objects at consecutive points along the path through which they are carried by said engagement members; walls enclosing the mentioned parts; 30 and means, comprising pairs of doors alternatively opened to permit the ingress and egress of said objects, without opening both of said doors at the same time.

9. In a preheating organization provided 40 with openings constantly closed by spaced and resiliently closing doors, a feeding mechanism comprising: a belt traveling over wheel members; engagement arms spaced along said belt; a rotating table placed adjacent to said belt member and extending beneath the path of said engagement arms; swingably mounted guide arms disposed along the path of said engagement arms; and means for resiliently holding said guide 45 arms in guiding position.

50 10. In a preheating organization comprising a treating chamber provided with openings constantly closed by spaced and resiliently closing doors; a plurality of carrying trays; a pair of belt members to which said trays are attached; wheel members over which said belt members travel; means comprising projecting arms and additional wheel members for maintaining said trays 55 substantially horizontal; means for feeding the objects which are to be treated onto like ends of said trays; guide bars, disposed to impart a continuous transverse movement to said objects during the movement of said carrying trays, causing said objects to be

carried through said treating chamber in a flattened, helical path corresponding to the flattened elliptical orbit through which said belt members move; discharge means whereby said objects are taken from said trays at 70 the end of their helical path; and walls enclosing the mentioned parts.

11. In a preheating organization comprising a heating chamber provided with openings constantly closed by spaced and resiliently closing doors, the combination of: a traveling member extending over a pair of sprocket wheels; carrying members arranged to be moved by said traveling members; means for moving said objects onto said carrying members in a direction parallel to the direction of travel of said traveling member; and means for causing said objects, while advancing in a flattened helical path, to pass repeatedly below and above 80 each of said sprocket wheels.

12. In a preheating organization comprising a heating chamber provided with openings constantly closed by spaced and resiliently closing doors, the combination of: a traveling member comprising upper and lower horizontal laps, carrying members arranged to be moved by said traveling member; an entrance trackway extending to a point adjacent to the path of said carrying members, the terminal point of said trackway lying in the same vertical plane of advance of said carrying members; means for moving said objects along said trackway onto said carrying members and means for causing said objects to be moved transversely on said carrying members during the advancement thereof.

13. In a preheating organization, comprising a treating chamber provided with openings constantly closed by spaced and resiliently closing doors, pivotally mounted in a vertical plane and movable by engagement with treating objects, the combination of: a traveling member provided with means for advancing said member over separate sprockets in a non-circular path; carrying members arranged to be moved by said traveling member; means for moving objects onto said carrying members in a direction parallel to the direction of travel of said traveling member; and means for removing said objects from said carrying members parallel to the direction of motion of said carrying members.

14. In a preheating organization, comprising a treating chamber provided with openings constantly closed by spaced and resiliently closing doors, pivotally mounted in a vertical plane and movable by engagement with treating objects, the combination of: a traveling member provided with means for advancing said members over separate sprockets in a non-circular path; carrying members arranged to be moved by said trav-

eling member; means for moving objects onto said carrying members in a direction parallel to the direction of travel of said traveling member; and means for removing said objects from said carrying members parallel to the direction of motion of said carrying members; said removing means comprising

a trackway and means for moving said objects along said trackway.

In testimony whereof, I have hereunto set ¹⁰ my hand at Riverside, California, this 29 day of October, 1923.

GEORGE WILCOX.
